PHOTOELECTRIC TUBE

Max Orlove, Chicago, Ill., assignor to Smith Industries, Chicago, Ill., a corporation of Illinois

Application May 2, 1945, Serial No. 591,560

7 Claims. (Cl. 250—165)

1

The invention relates to photo-electric tubes. One object of the invention is to improve photo-electric tubes to provide greater sensitivity and efficiency in response to light beams for modifying electric conditions in an electric circuit.

Another object of the invention is to provide a photo-electric tube with a cathode of a form which is efficient in operation.

Another object of the invention is to provide a photo-electric tube with an anode and magnet within the envelope of the tube.

Another object of the invention is to provide a combined anode and magnet within the envelope.

Another object of the invention is to provide a cathode with a resistor which decreases its resistance to current flow as the lumens increase.

Another object of the invention is to provide a cathode with a light-sensitive material which quickly releases electrons.

Other objects of the invention will appear from the detailed description.

The invention consists in the several features hereinafter set forth and more particularly defined by claims at the conclusion hereof.

In the drawings:

Fig. 1 is a longitudinal section of a photo-electric tube embodying the preferred form of the invention.

Fig. 2 is a horizontal section taken on line 2—2 of Fig. 1.

Fig. 3 is a detail illustration of the layers of elements on the cathode.

Fig. 4 is a view illustrating a modified form of combined magnet and anode.

Fig. 5 is a view illustrating another modified form of combined magnet and anode.

The invention is exemplified in a photo-electric tube which comprises an envelope or bulb 8 made of glass, and provided with a cylindrical body-portion 9, a base 11 and a stem 12, which are sealed in the usual manner, and a convex outer-end 13 which is light-pervious. Between convex end 13 and base 11 the envelope 8 is coated with carbon black 8a to render it light-imperious. A casing or jacket 14 fits around and re-enforces the envelope 8. A socket 15 is secured around base 11 in jacket 14 in the usual manner. Prongs 17 and 18 are secured in socket 15 for connection to a socket having terminals connected to an electric circuit which is to be modified or controlled by the operation of the photo-electric tube.

The cathode, generally designated 22, is in the form of a tube of truncated-conoidal form having its axis co-axial with the envelope 8 and anode 20 and its inner periphery is divergent or flared to

ward the curved light-pervious end 13 of the envelope. The conoidal cathode extends longitudinally from a point adjacent stem 12 to a point adjacent the end 13 of the envelope so that it will be of the maximum length and internal area permitted by the available space in and according to the length of the envelope, for providing the maximum area for the photo-electric sensitive material on its inner periphery, which receives incoming energizing light through the light-pervious end 13 of the envelope 8. The electrons released by the cathode are proportionate to the area of the inner periphery of the cathode and the greater said area the greater the electrons released thereby, and therefore it is desirable to provide the maximum area in the inner periphery of the cathode to which the photo-sensitive material is applied and to provide a completely conoidal cathode. The outward divergence of the inner periphery of the cone is such that the incoming energizing light will strike the inner periphery of the conoidally tubular cathode at angles of incidence which will cause the generated electrons to be impacted angularly, longitudinally and transversely in the cathode, to the anode, and back and forth between different peripheral portions of the cathode, for producing secondary electrons.

The cathode is formed of thin copper or nickel, silver-plated or nickel-plated and its inner periphery is polished. Preferably, the cathode is formed of seamless tubing. A coating *a* of selenium, one atom in thickness, is applied to the polished inner periphery of the cathode. A coating *b* of uranium oxide, substantially of molecule thickness, is applied to the coating *a*. A coating *c* of light or photo-sensitive material is applied to the oxide coating. This light-sensitive material preferably consists of virginium, either in its natural state or mixed with cesium or rubidium. Virginium is highly sensitive to impinging light, particularly in the range of the lower red band of the spectrum and quickly releases electrons. Virginium, known as element 87, has been found to be the heaviest in the atomic scale of light-sensitive elements. The selenium layer on the cathode acts as a resistor which decreases its resistance to current flow as the lumens increase. The uranium oxide acts as a battery by generating additional potential with the flux of light. The virginium or virginium and cesium or rubidium act as electron-releasing elements or alkali metals. The inert gas acts to emit additional electrons and in reverse to stabilize the free electrons. With the horse-shoe magnet hereinafter described acting as an anode, a strong magnetic field is pro-

duced which influences the path and therefore the density of a heavy krypton gas.

The anode, generally designated 20 is in the form of a strip of wire which is anchored in stem 12 and extends longitudinally from said stem and axially of the envelope 8 to a point near the light-pervious end 13 of the envelope, and its inner end is electrically connected to prong 18 for connection to the positive side of the electric circuit. The anode is preferably formed of approximately 50% iron, 11% aluminum, 14% nickel, and 24% cobalt.

The anode is connected to the positive side of the electric circuit. A strip of wire 25 of the same compositions as the anode and, for example, $\frac{1}{8}$ th inch thickness, highly and permanently magnetized, is welded as at 26 to the anode 20 and extends laterally therefrom and thence upwardly between the cathode and the wall of the envelope 8, so as to form with the anode, a horse-shoe magnet. The wire of the anode becomes magnetized from the strip 25. This magnetic structure constitutes a combined anode and magnet which carries a positive electro-static charge and boosts the agitation, collision and ionization of the inert gas in the envelope to produce the release of additional secondary electrons from the inert gas, and attracts some of the electrons moving closely to the anode and bends others out of their straight paths. This ionization of the agitated gas atoms and molecules releases additional electrons from the gas and increases the efficiency of the tube. This anode and magnet structure, being of horse-shoe form, can be disposed entirely within the envelope for direct influence upon the atoms and molecules. The wire of the anode in the cathode is of small cross-sectional area and extends coaxially of the tubular cathode where the least shadows will be produced. The wire of the anode may also be extended laterally as at 20' to reduce the magnetic gap between the ends of the anode wire and strip 25.

A light reflector 28 of disk form is provided at the opening in the inner or constricted end of the conoidal cathode and may be supported by a wire 30 anchored in stem 12 for independently reflecting light from the inner end of the cathode back into it. This reflector 28 may also be supported or connected to either the cathode or the anode. If the reflector is connected to the cathode, its reflecting face will be provided with the same coating as the inner periphery of the cathode. If the reflector is supported on the anode or independently, no coating is necessary. The reflector is preferably formed of polished nickel or silver-plated copper and has a convex face, and has a flat rim which projects outwardly of the adjacent end of the tubular cathode so it may reflect some of the light to the outer periphery of the cathode.

In operation, light enters the photo-electric tube through the light-pervious convex outer end 13 of the envelope 8. The anode 20 and cathode 22 are electrically connected to the prongs 17 and 18 which are connected respectively to negative and positive sides of an electric circuit. The energizing light entering the envelope 8 will close the circuit between the anode 20 and the cathode 22. The incoming light causes the photosensitive material on the inner periphery of the cathode to release the electrons which carry a charge of negative current to close the circuit. The electrons released by the material on the conoidal periphery of the cathode will be refracted angularly from said periphery. Some of the electrons will strike

the anode. Others which by-pass the anode will be impacted to the opposite side of the inner periphery of the cathode and will collide with and ionize the gas and cause additional release of electrons from the gas, as well as from the cathode wall upon which it impinges. Some of the electrons will be impacted back and forth or in a zig-zag path across the space in the cathode. The anode carrying the positive electro-static charge, as well as the magnetic force, will disrupt the electrons from the cathode and render them more susceptible to rebound from the photo-sensitive material and accelerate the drawing of electrons to the anode. The electrons which pass close to the anode will be more readily captured while the floating electrons will be deflected out of a straight path. This will increase the electrons released and increase the efficiency of the photo-cell. The ions are positively charged and act in reverse as the electrons but help to stabilize the workability owing to the magnet. The reflector 28 at the inner end of the cathode 22 also reflects electrons and light back into the conoidal cathode. The conoidal cathode is preferably seamless, may be of the maximum length, according to space available in envelopes of different sizes, and its conoidal form provides maximum area for the photo-sensitive surface, and causes the electrons to be reflected back and forth in the cathode, as well as the entered light.

In the modification illustrated in Fig. 4, the anode comprises a pair of substantially parallel strips 31 of nickel wire cross-connected at their inner ends by a strip 32 of Alnico wire which has been highly and permanently magnetized up to the saturation point. Strip 32 is connected to the conductor which leads to the positive side of the electric circuit. In this construction, the cross-strip 32 magnetizes the anode members 31 to render the anode magnetic.

In the modified form of the invention illustrated in Fig. 5, the anode is formed of a strip of Alnico wire magnetized to the point of saturation, so that it will function as a combined anode and bar magnet within and extending longitudinally of the cathode. In this construction, the atoms become ionized owing to the loss of an electron and the positive ions will be either drawn or repelled from the magnet owing to its opposite polarity.

The invention is not to be understood as restricted to the details set forth, since these may be modified within the scope of the appended claims without departing from the spirit and scope of the invention.

Having thus described the invention, what I claim as new and desire to secure by Letters Patent is:

1. A photo-electric tube comprising: a sealed glass envelope provided with an end portion pervious to light; a cathode provided on one of its faces with a photo-electric sensitive material containing virginium; and an anode of wire within the envelope and extending longitudinally of the cathode.

2. A photo-electric tube comprising: a sealed glass envelope provided with an end portion pervious to light; a cathode extending longitudinally of the envelope and provided on one of its faces with a photo-electric sensitive material containing virginium and one or more of the group including cesium and rubidium and an anode of wire within the envelope and extending longitudinally of the cathode.

3. A photo-electric tube comprising: a sealed

envelope provided with an end portion pervious to light; a cathode extending longitudinally in the envelope and provided with a photo-electric light-sensitive material on its inner periphery for receiving light from said light-pervious portion; and a combined anode and magnet in the envelope.

4. A photo-electric tube comprising: a sealed envelope provided with an end portion pervious to light; a cathode of tubular form extending longitudinally in the envelope and provided with a light-sensitive material on its inner periphery for receiving light from said light-pervious portion; and a combined anode and horse-shoe magnet in the envelope.

5. A photo-electric tube comprising: a sealed glass envelope provided with an end portion pervious to light; a cathode of tubular form extending longitudinally in the envelope and provided with a light-sensitive material on its inner periphery for receiving light from said light-pervious portion; and a combined anode and bar-magnet extending longitudinally of and within the cathode.

6. A photo-electric tube comprising: a sealed glass envelope provided with an end portion pervious to light; a cathode of tubular form extending longitudinally of the envelope and provided with a photo-electric sensitive material on its inner periphery for receiving light from said light-pervious portion; and an anode including a permanently magnetized wire within the cathode.

7. A photo-electric tube comprising: a sealed glass envelope provided with a portion pervious to light; a cathode extending longitudinally of the envelope and for receiving light from said light-pervious portion and provided with a photo-electric sensitive material; and an anode including a wire and a permanently magnetized member forming a horse-shoe magnet extending longitudinally of the cathode.
